UNITED STATES PATENT OFFICE.

OSCAR B. PULIS, OF MILWAUKEE, WISCONSIN, ASSIGNOR TO METAL FORMS CORPORATION, OF MILWAUKEE, WISCONSIN, A CORPORATION.

ALIGNER-BAR-ENGAGING BRACKET FOR CONCRETE FORMS.

Application filed June 12, 1922. Serial No. 567,528.

To all whom it may concern:

Be it known that I, OSCAR B. PULIS, a citizen of the United States, residing at Milwaukee, in the county of Milwaukee and State of Wisconsin, have invented certain new and useful Improvements in Aligner-Bar-Engaging Brackets for Concrete Forms, of which the following is a specification.

It is now quite common practice in concrete construction work to fabricate forms by assembling a number of standardized form units and locking them together in the required relation to each other. For straight work these form units may be conveniently made rectangular in shape, and they are ordinarily assembled in superposed horizontal rows. The abutting edges of the assembled form are securely locked together, and when a large panel is formed it is desirable to provide brace or aligner bars at the back of the panel to prevent the panel from bulging or giving away at places under the heavy pressure of the plastic concrete.

With this consideration in view, the object of the present invention has been to provide a novel form of bracket for securing the brace or aligner bars to the rows of form units. Great flexibility is necessary in the assembling of these units to meet the different requirements, and the bracket is detachable so that it can either be applied to the form unit or omitted, as may be necessary or desired.

Among the further objects of the invention is to provide an aligner bar engaging bracket of this character which is comparatively simple and inexpensive in its construction, which can be readily applied to the form unit or detached therefrom, and which will hold the aligner bar securely in position against the back of the unit.

For the purpose of illustrating the invention, one particular embodiment thereof has been shown on the drawings and will be described in detail, although it will be understood that many modifications and changes can be made in the details of construction without departing in any manner from the spirit of the invention.

Reference is to be had to the following

description and accompanying drawings, in which,

Figure 1 is an elevation showing an assemblage of four standard rectangular form units together with associated horizontal and vertical aligner bars, the form units being illustrated by dotted lines since they form no part of the present invention, and the horizontal aligner bars being shown as attached to the form units by means of brackets which are constructed in accordance with the invention.

Figure 2 is an enlarged elevation of one of the brackets, showing the same as engaging the form aligning bar and as applied to a form unit.

Figure 3 is an edge view of the bracket member, showing the same in operative position.

Figure 4 is a view similar to Figure 1, showing a bracket member which is of double size and is intended to engage the overlapping ends of a pair of aligner or brace bars.

Figures 5 and 6 are detail views showing a modified form of the invention in which the fastening members for securing the brackets in position are carried by the brackets so that they are not liable to be misplaced or lost.

Corresponding and like parts are referred to in the following description and indicated on all of the views of the drawings by like reference characters.

Referring to the drawings, and more particularly to Figure 1, the reference characters A designate standard rectangular form units which are of a conventional and well known construction and form no part of the present invention. These standard form units are adapted to be assembled in different relations to meet different requirements, and for forming a wall they are assembled in a panel comprising superposed horizontal rows of the units. A panel comprising four of the units is shown for illustrative purposes. The specific construction of the units themselves is not material, although it may be explained that each of the units A comprises a sheet metal body plate 1 which is surrounded by a marginal flange provided by angle iron strips 2,

Each of the units is also provided with a T iron strip 3 extending transversely across the back thereof in one direction at substantially the center of the unit. These 5 intermediate stiffening strips 3 provide convenient outstanding flanges for the attachment of the brackets or clamps B of the present invention.

In order to prevent bulging of the panel 10 which is formed by assembling the units A, horizontal aligner or brace bars 4 extend along the horizontal rows of the units at the back thereof, being in direct engagement with the form units, and these horizontal 15 aligner bars 4 are in turn braced at suitable intervals by vertical bars 5. These aligner or brace bars may be formed of any suitable material. Either wooden bars or any desired standard sections of structural 20 steel, such as angle or channel iron, may be used. One set of the intersecting aligner or brace bars, in the present instance the horizontal bars 4, are attached directly to the form units A, while the other set of bars, in 25 the present instance the vertical bars 5, are secured to the horizontal bars at their joints of intersection. For this purpose any suitable clamps such as those indicated at 6 may be used. These clamps are in the form of U 30 shaped bails which straddle the vertical bars 5 and engage the horizontal bars 4, said bails being provided at their outer ends with eccentrics or cams 7 which can be tightened to draw the aligner bars tightly together at their points of intersection. A rigid backing frame is thus provided for holding the panel of assembled units A rigidly in position and preventing any possible 35 bulging thereof.

40 The brackets B for attaching the horizontal aligner bars 4 to the horizontal rows of units A preferably have a substantially U shaped formation so that they straddle the bars. The free ends of the U shaped brackets B detachably engage the stiffening flanges 3 of the units and a cam or wedge means is provided for bringing the horizontal bars into a firm engagement with the units. For this purpose the ends of the U 45 shaped bracket are provided with slots which are adapted to register with corresponding slots 8 in the stiffening flange 3 and to receive locking wedges 9.

50 In the particular form of bracket B which has been illustrated, the arms of the bracket are bifurcated so that they fit over and straddle the stiffening rib 3. The brackets may be conveniently constructed, as illustrated, by interposing an intermediate or 55 filler plate 10 between the outer end portions of a pair of U shaped plates 11, the three thicknesses being fastened together in any suitable manner as by means of the rivets 12. The free ends of the bracket arms thus have 60 a bifurcated formation so that they can

straddle the stiffening flange 3 of the form units, as indicated quite clearly by Figure 3. When the wedge members 9 are driven in position the bracket B is caused to tightly engage the aligner bar 4 and draw it into a firm engagement with the back of the form unit A.

65 For use in splicing the ends of a pair of horizontal bars 4, a double size bracket may be used, such as that indicated at C on Figure 1, and illustrated in detail by Figure 4. The ends of the two horizontal bars which are to be spliced are permitted to overlap and are engaged by two of these double size brackets C. The brackets C have substantially the same construction as the brackets B, but are merely made sufficiently large to receive two of the aligner bars 4. It will be noted that the stiffening flange 3 of each of the form units A is provided with three or more of the slots 8, and these slots are so positioned that either a small bracket B or a large bracket C can be readily applied to the unit.

70 A slight modification is illustrated by Figures 5 and 6, in which the bracket or clamp members are shown as provided with the fastening means for securing them to the form units. The bracket member D has substantially the same construction as the bracket member B, and is adapted to be applied to the aligner bar and form unit in the same manner. Each side of the bracket D is provided with a swinging arm 13, which is pivotally mounted at 14 between a pair of outstanding ears 15. The swinging end of the arm is provided with a finger piece 16 and also with a wedge shaped finger 17 which is adapted to be swung through the aligning slots of the bracket member and stiffening flange of the form unit. The wedge locking element is thus carried by the bracket member so that it is always in position for use, and there is no danger of the wedge member becoming accidentally misplaced or lost. If desired or necessary a slot or loose joint may be provided at the pivotal connection 14 so that there will be nothing to prevent a proper functioning of the wedge member when it is swung into operative position.

75 It will be obvious that these aligner bar engaging brackets can be employed in connection with the panels or units which are utilized in making circular, curved or irregular walls, and that the aligner bars themselves may either be composed of wooden bars or any suitable type of metal bar, such as of angle iron or channel iron members.

80 Having thus described my invention what I claim as new and desire to secure by Letters Patent is,

85 1. The combination with a form unit and an aligner bar, of a U-shaped bracket straddling the aligner bar, and fastening mem-

bers for positively attaching the respective arms of the **U**-shaped bracket to the unit and at the same time forcibly drawing the bracket toward the unit to clamp the aligner bar in position.

2. The combination with a form unit and an aligner bar, of a **U**-shaped bracket straddling the aligner bar, the unit and both arms of the bracket being formed with portions which overlap and are provided with corresponding openings, and keys insertable through the openings to fasten the respective arms of the bracket to the unit.

3. The combination with a form unit provided with a flange, an aligner bar, a bracket engaging the aligner bar and having an overlapping and sliding engagement with the flange, and wedge means for securing the bracket to the flange and at the same time forcibly sliding it relative thereto to clamp the aligner bar in position.

4. The combination with a form unit, an aligner bar, a bracket engaging the aligner bar and having an overlapping engagement with a portion of the form unit, said overlapping portions being provided with corresponding openings, fastening keys insertable through the said openings, and swinging members mounted upon one of the members and carrying the keys.

5. The combination with a form unit constructed with a flange, an aligner bar, a **U**-shaped bracket straddling the aligner bar and having the arms thereof in an overlapping and sliding engagement with the flange of the unit, the flange and arms of the bracket being formed with corresponding openings, and pivotally mounted keys car-

ried by the brackets and insertable through the openings to secure the brackets in position.

6. The combination with a form unit having an outstanding flange, of an aligner bar engaging bracket having a bifurcated portion fitting over the flange, and means for detachably securing the said bifurcated portion of the bracket to the flange.

7. The combination with a form unit having an outstanding flange, of an aligner bar engaging bracket having a bifurcated portion adapted to fit over the flange, the bifurcated portion of the flange being formed with corresponding openings, and locking means insertable through the corresponding openings to detachably secure the bracket to the form unit.

8. The combination with a form unit having an outstanding flange, a **U** shaped bracket adapted to straddle an aligner bar and having bifurcated ends adapted to fit over the flange of the form unit, and means for detachably securing the bifurcated ends of the bracket to the flange of the form unit.

9. The combination with a form unit having an outstanding flange, of a **U** shaped bracket adapted to straddle an aligner bar and having bifurcated ends adapted to fit over the flange, the flange and arms of the bifurcations being correspondingly slotted, and wedge members insertable through the slots for detachably securing the bracket to the form unit.

In testimony whereof I affix my signature.

OSCAR B. PULIS.
